US0D1016485S

(12) **United States Design Patent** (10) **Patent No.:** **US D1,016,485 S**
(45) **Date of Patent:** ** *Mar. 5, 2024

(54) **SUITCASE**

(71) Applicant: **YETI Coolers, LLC**, Austin, TX (US)

(72) Inventors: **Derek G. Sullivan**, Austin, TX (US);
Steve Charles Nichols, Austin, TX (US); **Christopher Kalek**, Austin, TX (US)

(73) Assignee: **YETI Coolers, LLC**, Austin, TX (US)

(*) Notice: This patent is subject to a terminal disclaimer.

(**) Term: **15 Years**

(21) Appl. No.: **29/855,697**

(22) Filed: **Oct. 6, 2022**

Related U.S. Application Data

(63) Continuation of application No. 29/763,680, filed on Dec. 23, 2020.

(51) **LOC (14) Cl.** **03-01**

(52) **U.S. Cl.**

USPC **D3/279**

(58) **Field of Classification Search**

(57) **CLAIM**

The ornamental design for a suitcase, as shown and described.

DESCRIPTION

FIG. 1 is a front perspective view of a suitcase showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depicting the remainder of the suitcase form no part of the claimed design.
